Primary Examiner — Keli L Hill*Assistant Examiner* — Sara S Sahneh(74) *Attorney, Agent, or Firm* — Vangelis Economou; Ziliak Law, LLC(57) **CLAIM**

The ornamental design for an electronic lock, as shown and described.

DESCRIPTION

FIG. 1 is a perspective view of the electronic lock showing my new design;

FIG. 2 is a top view thereof;

FIG. 3 is a bottom view thereof;

FIG. 4 is a front elevational view thereof;

FIG. 5 is a back elevational view thereof;

FIG. 6 is a left side view thereof; and,

FIG. 7 is a right side view thereof.

The broken lines shown are included for the purpose of illustrating portions of the electronic lock that form no part of the claim.

1 Claim, 4 Drawing Sheets(56)
